UNITED STATES PATENT OFFICE.

HANS L. RUED, OF BUTTERFIELD, MINNESOTA.

SAFETY ATTACHMENT FOR WHIFFLETREES.

No. 889,722.

Specification of Letters Patent.

Patented June 2, 1908.

Application filed September 17, 1907. Serial No. 393,289.

To all whom it may concern:

Be it known that I, HANS L. RUED, a citizen of the United States, residing at Butterfield, in the county of Watonwan and State 5 of Minnesota, have invented a new and useful Safety Attachment for Whiffletrees, of which the following is a specification.

The invention relates to a safety attachment for whiffletrees.

10 The object of the present invention is to provide a simple and inexpensive device of great strength and durability, adapted to be readily applied to the tongue or pole, and capable of equalizing the draft and of preventing 15 the latter from pulling the tongue or pole either upwardly or downwardly to afford a straight pull, and to prevent the necks of the horses, or other draft animals from becoming sore.

20 A further object of the invention is to provide a device of this character, adapted to prevent the swingletrees from dropping to the ground should their pivot bolts become broken.

25 With these and other objects in view, the invention consists in the construction and novel combination of parts hereinafter fully described, illustrated in the accompanying drawing, and pointed out in the claims here- 30 to appended; it being understood that various changes in the form, proportion, size and minor details of construction, within the scope of the claims, may be resorted to without departing from the spirit or sacrificing 35 any of the advantages of the invention.

In the drawing:—Figure 1 is a reverse plan view of a safety attachment, constructed in accordance with this invention and shown applied to a pole and its whiffletrees. 40 Fig. 2 is a transverse sectional view of the same. Fig. 3 is a detail sectional view on the line $x-x$ of Fig. 2. Fig. 4 is a detail perspective view of the attachment.

Like numerals of reference designate corresponding parts in all the figures of the drawing.

The safety attachment comprises an evener bar or member 1, centrally pivoted to the lower face of a tongue or pole 2 and provided at its ends with upwardly extending substantially S-shaped clips or supports 3, which receive the ends of a doubletree 4 and swingletrees 5. The bar 1, which has a flattened central portion 6 to fit the lower face of 55 the tongue or pole 2, is provided with a central perforation 7 for the reception of a pivot

bolt 8 of the doubletree. The side portions of the bar 1 are arranged at a slight inclination and extend upwardly and outwardly, as clearly illustrated in Figs. 2 and 4 of the 60 drawing.

The ends of the bar 1 terminate at the ends of the doubletree, and the clips or supports 3, which are rigid with the bar 1, extend upwardly therefrom and consist of upper loops 65 9 and reversely arranged lower loops 10. The upper loops are open at the front and form recesses to receive the ends of the doubletree, and the lower loops, which are open at the back, also form recesses to receive the 70 central portions of the swingletrees 5, which are interposed between the doubletree and the bar 1, thereby affording a straight central pull and preventing the draft from pulling the tongue or pole either upwardly or 75 downwardly. By this construction, the attachment operates to equalize the draft and while it strengthens and braces the whiffletrees, it, by affording a central pull, prevents the necks of the horses, or other draft ani- 80 mals from getting sore. The whiffletree bolts 11 pierce the supports or clips, the top, intermediate and bottom portions of the supports or clips being provided with alined perforations for the reception of the said bolts 85 11. Should the whiffletree bolts break, the strain on the harness will operate to draw the swingletrees forwardly in the lower loops 10, which will be held tightly against the ends of the doubletree by the traces, and by this con- 90 struction and arrangement, the swingletrees will be prevented from dropping to the ground. Also the clips or supports do not present any projecting portions on which the lines may catch. The clips or supports are 95 provided at the bottom portions of the lower loops with rearwardly projecting eyes 12, adapted to receive stay straps or chains (not shown.)

Having thus fully described my invention, 100 what I claim as new and desire to secure by Letters Patent, is:—

1. The combination of a pole, a doubletree located wholly above and pivoted to the upper face of the pole, swingletrees pivoted to 105 the doubletree and arranged beneath the end portions of the same and located in the same horizontal plane as the pole to centralize the draft, of a safety attachment comprising a bar or member centrally pivoted to the lower face of the pole, and end supports formed integral with and extending upwardly from the 110

bar or member and receiving and embracing the swingletrees and the ends of the doubletrees at the pivotal points of the said swingletrees.

5. 2. The combination with a pole, a doubletree, and swingletrees located below the doubletree, of a safety attachment comprising a bar or member centrally pivoted to the lower face of the pole, end supports rigid with the 10 bar or member and having upper and lower loops receiving the doubletree and the swingletrees, and pivots piercing the doubletree, the swingletrees and the supports.

15. 3. As a new article of manufacture, a safety attachment for whiffletrees consisting of a bar or member adapted to fit against the lower face of a pole and provided with a central perforation to receive the central pivot of a doubletree, and substantially S-shaped 20 supports formed integral with and extending upwardly from the ends of the said bar or member and having upper and lower loops to receive and embrace the ends of the doubletree at the central portions of the swingletrees, said supports being also provided with 25 openings for the pivots of the swingletrees.

30. 4. The combination with a pole, a doubletree, and swingletrees located beneath the doubletree, of a safety attachment comprising a bar or member pivoted to the lower face of the pole, and substantially S-shaped terminal supports consisting of upper loops open at the front and receiving the ends of the doubletree, and lower loops open at the

back and receiving the swingletrees, and pivots securing the doubletree and the swingletree to the supports. 35

5. A safety attachment for poles and whiffletrees comprising a centrally pivoted bar or member, and terminal supports integral with the bar or member and having reversely arranged loops adapted to receive swingletrees and the ends of a doubletree at the pivotal points of the swingletrees. 40

6. The combination with a pole, a doubletree located wholly above and pivoted to the upper face of the pole, and swingletrees pivoted to the ends of the doubletree and arranged beneath the end portions of the same and located in the same horizontal plane as the pole to centralize the draft, of a safety attachment comprising a bar or member centrally pivoted to the lower face of the pole, terminal supports formed integral with the bar or member and provided at the front and back with recesses to receive the swingletrees and the doubletree, and eyes projecting rearwardly from the bottom of the supports and adapted to be connected with stay straps or chains. 45 50 55 60

In testimony, that I claim the foregoing as my own, I have hereto affixed my signature in the presence of two witnesses.

HANS L. RUED.
